CLAIM

The ornamental design for a cab for a construction machine, as shown and described.

DESCRIPTION

FIG. 1 is a front, top and right side perspective view of a cab for a construction machine showing our new design;
 FIG. 2 is a rear, top and left side perspective view thereof;
 FIG. 3 is a left side view thereof;
 FIG. 4 is a right side view thereof;
 FIG. 5 is a top plan view thereof;
 FIG. 6 is a bottom plan view thereof;
 FIG. 7 is a rear view thereof; and,
 FIG. 8 is a front view thereof.
